UNITED STATES PATENT OFFICE.

FRANK DUTCHER, OF VERSAILLES, PENNSYLVANIA, ASSIGNEE TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,102,889.

Specification of Letters Patent.

Patented July 7, 1914.

Application filed June 8, 1912. Serial No. 702,594.

To all whom it may concern:

Be it known that I, FRANK DUTCHER, a citizen of the United States, residing at Versailles, in the county of Allegheny and State of Pennsylvania, have invented certain new and useful Improvements in Railway Signal-Torpedoes, of which the following is a specification, reference being had therein to the accompanying drawing.

10 My invention relates to improvements in railway signal torpedoes, and the object of which is to make a torpedo having a case made from a fiber sheet which is folded around the explosive compound and passing 15 the lead rail attaching strip through openings in adjacent folded ends of the sheet and cementing the folded ends and the rail-engaging strip to the folded body-portion of the case, whereby an efficient, durable and 20 cheap fiber torpedo is produced.

In the accompanying drawings—Figure 1 is a top plan view of my preferred form, shown attached to a railroad rail. Fig. 2 is an inverted perspective view of the completed torpedo. Fig. 3 is a sectional view on the line 3—3 of Fig. 1. Fig. 4 is a sectional view on the line 4—4 of Fig. 1. Fig. 5 is a perspective view of the case, partially folded, the explosive container and the explosive, the parts being shown in separated relation. Fig. 6 is a perspective view of a modified form of my improved torpedo, showing it attached to a railroad rail. Fig. 7 is an inverted perspective view of the modified form. Fig. 8 is a sectional view on the line 8—8 of Fig. 6. Fig. 9 is a sectional view on the line 9—9 of Fig. 8. Fig. 10 is a perspective view of the blank of the modified form shown in operative position 40 with the explosive compound block in position ready to have the case folded around it.

Referring now to Figs. 1 to 5, inclusive, the case of my preferred form is formed from a fiber sheet 1, which is overlapped at 45 its center, as shown at 2, with the ends of the sheet projecting beyond the explosive which is contained within the case or tube 1, thus formed. Preferably the block of the explosive compound 3 is placed within a 50 tubular fiber container 4, and around which the sheet is folded. By reference to Fig. 5 it will be noted that after the edges of the sheet have been overlapped, the edges of the 55 projecting ends 5 are crimped, as shown at 6, to be folded in to form the end 7. The

blank sheet has perforations 8, which register when the ends are folded, as shown at 7. Suitable cement 9 is placed on the body of the case and the lead engaging strap 10 is passed through these openings, as shown in Fig. 2, the cement thus serving to unite the overlapping ends 7 and the strap 10 to the body of the case.

The modified form of torpedo is made from a blank, as shown in Fig. 10, in which the blank has the end flaps 11, which are provided with strap receiving openings and also the narrow end flaps 13. The blank also has the side flaps 14. These side flaps 14 are folded in on the explosive block 15, and the narrow end flaps 13 overlapping and extending along the ends of the explosive block 15, the end flaps 11 are then closed over the body of the torpedo and overlapped. The rail-engaging strip 16 is passed through 75 the openings 12, as shown in Fig. 7, and the end flaps 11 are suitably cemented together and preferably the lead strip cemented at 17.

Having thus described my invention, what I claim and desire to secure by Letters Patent is—

1. A railway signal torpedo, comprising an explosive compound and a case therefor consisting of a sheet having its sides and ends folded therearound and overlapping 85 each other, the folded ends provided with alined openings having surrounding walls and a rail-engaging strip passing through said openings.

2. A railway signal torpedo, comprising 90 an explosive compound, a case therefor consisting of a sheet having its sides and ends folded therearound and overlapping the folded ends of the sheet located outside of the folded sides, the overlapping ends provided with alined openings when folded and having surrounding walls and a rail-engaging strip passing through said openings.

3. A railway signal torpedo comprising 100 an explosive compound, an inclosing case therefor, consisting of a sheet folded over the compound with overlapping edges, the sides of the ends of the sheet folded inward, said ends of the sheet folded transverse the first-mentioned folds and over the body of 105 the case and cemented thereto and having strip-receiving openings, and a rail-engaging strip passing through said openings.

4. A railway signal torpedo, comprising 110 an explosive compound, an inclosing case

therefor consisting of a sheet folded over the compound with overlapping edges, the sides of the ends of the sheet folded inwardly and the folded ends folded over upon the body of the case and cemented thereto, and a rail-engaging strap passing through the folded ends longitudinally thereof and longitudinal of the torpedo.

5. A railway signal torpedo, comprising an explosive compound, an inclosing case therefor, consisting of a sheet folded over the compound with over-lapping edges, the

sides of the ends of the sheet folded inwardly, said folded ends resting upon the body of the case and cemented thereto, and 15 a rail-engaging strap interlocking with the folded ends and securing the same together substantially as shown and described.

In testimony whereof I hereunto affix my signature in the presence of two witnesses. 20

FRANK DUTCHER.
